A. E. FOWLE

SHEET FLATTENING MEANS

Filed Jan. 30, 1925

INVENTOR -
Arthur E. Fowle.
Frank Fraser,
ATTORNEY.

UNITED STATES PATENT OFFICE.

ARTHUR E. FOWLE, OF TOLEDO, OHIO, ASSIGNOR TO THE LIBBEY-OWENS SHEET GLASS COMPANY, OF TOLEDO, OHIO, A CORPORATION OF OHIO.

SHEET-FLATTENING MEANS.

Application filed January 30, 1925. Serial No. 5,722.

The present invention relates to a method and apparatus for producing sheet glass, and has particular reference to means associated with a sheet glass apparatus for removing surface defects in the sheet whereby to produce a flat, uniform sheet.

An important object of the invention is to provide means for drawing a sheet from a mass of molten glass, and means over which the sheet may be dragged to flatten the same.

A further object of the invention is to provide means for drawing a sheet from a mass of molten glass, and includes means for deflecting the sheet into substantially a horizontal plane, and has means closely adjacent to the deflecting means over which the sheet is dragged to flatten or iron out any surface irregularities which may be present.

Still another object of the invention is to provide an apparatus wherein a sheet of glass is drawn from a mass of molten glass and deflected into a horizontal plane, the said sheet being supported upon and dragged over a non-corrosive member to flatten the same.

Still another object is to provide, in combination with a sheet drawing apparatus, a non-corrosive slab over which the sheet being drawn may be dragged to flatten the same; said apparatus including means for heating the sheet as it passes over the flattening means, and also means for absorbing heat after the sheet has been flattened.

Other objects and advantages of the invention will become apparent during the course of the following description.

In the drawings wherein like numerals are employed to designate like parts throughout the same.

Fig. 1 is a vertical longitudinal section through a portion of an apparatus showing my invention in use, and

Fig. 2 is a similar view showing a slightly modified construction.

This invention is primarily designed for use in connection with the machine disclosed in the patent to Colburn, 1,248,809, granted December 4, 1917. It is to be understood however that the invention is not necessarily restricted to such a machine as it can well

be adapted to any form of sheet drawing apparatus.

In the Colburn process above referred to the sheet 5 is drawn from a mass of molten glass 6 contained in a so-called draw-pot 7. The sheet is drawn in a vertical plane and is deflected over a bending roll 8 into a horizontal plane where it is run over a draw-table 9 and on through a suitable annealing leer. The knurled rolls 10 are provided at the edges of the sheet to engage the same for maintaining the sheet to width after it has left its source 6.

In the Colburn process there is a so-called idler roll positioned between the bending roll 8 and the end of the draw-table 9. The sheet, after being deflected over the bending roll 8, has a tendency to sag between the bending roll and idler roll, and the idler roll and draw-table. The sheet is heated by a flame from the burner 10 as it is being deflected, and this further increases the tendency of the sheet to sag with the resultant strain on the same which may produce waves or other surface irregularities.

In the present invention the idler roll used in the Colburn machine is removed and a non-corrosive slab 11 is substituted. The slab 11 may be formed from any non-corrosive material such as nickel, nichrome, monel, graphite or the like. The slab 11 is supported upon a hollow casting 12 which is carried by the cross-members 13. The casting 12 may be internally heated or cooled as desired.

The upper surface of the slab 11 which comes in contact with the sheet 5 is preferably highly polished so that the sheet may be dragged thereover to flatten the same without injury to its surface. To facilitate flattening, flames may be applied from the burners 14, which will soften the glass sufficiently to permit it to be dragged to a uniform smoothness and flatness over the slab 11.

To prevent impressions from the draw-table 9, heat-absorbing means in the nature of a cooler may be positioned as at 15. The slab 11 will support the sheet during its travel from the bending roll 8 to the draw-table 9, while at the same time it will produce a wiping effect on the sheet which will

have a tendency to flatten or make uniform its surface.

In Fig. 1, the forward end of the slab 11 is slightly arcuated, as indicated by the numeral 16, which necessitates a lowering of the bending roll. The sheet is bent through a wider arc in the disclosure shown in Fig. 1 than in Fig. 2, thus the wiping effect is increased.

Although the burners 14 are shown in both figures of the drawings it is to be understood that they are not necessarily essential to the proper functioning of the slab 11, as the sheet is in a fairly heated condition after it has passed over the bending roll 8. By supporting the sheet upon the slab 11, strains, thin portions, and other defects will not be as apt to be found in the finished sheet. In addition to supporting the sheet, it is flattened out by the dragging and wiping effect so that a good flat, smooth and uniform thickness of sheet is produced.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

Claims:

1. In sheet glass apparatus, a receptacle containing a mass of molten glass, a bending roll, a draw-table for drawing a sheet from the mass of molten glass, said sheet being deflected over the bending roll into substantially a horizontal plane, a non-corrosive alloy member arranged between the bending roll and the draw-table for supporting the sheet and over which the sheet may be dragged to flatten the same, means for heating the sheet as it passes over the flattening member, and means for absorbing heat from the sheet after it has passed over the flattening member and before it comes in contact with the draw-table.

2. In sheet glass apparatus, a receptacle containing a mass of molten glass, a draw-table for drawing a sheet therefrom, means over which the sheet may be dragged to flatten said sheet before it reaches the draw-table, and means for absorbing heat from the sheet after it has passed over the flattening means and before it passes over the draw-table to prevent draw-table impressions thereon.

3. The process of producing sheet glass, consisting in drawing a sheet from a mass of molten glass, reheating the same, then dragging the sheet over non-corrosive means for flattening the same, and then absorbing heat from said sheet as it leaves said flattening means.

4. The process of producing sheet glass, consisting in drawing a sheet from a mass

of molten glass, and then dragging the sheet in a curved path over a member of a shape adapted to produce a wiping effect for removing irregularities in the sheet surface.

5. In sheet glass apparatus, a receptacle 70 containing a mass of molten glass, drawing means for drawing a sheet of glass from said mass, means arranged in advance of the drawing means and over which the sheet is dragged to flatten the same, means for 75 heating the sheet as it is dragged over said member, and means for absorbing heat from the sheet after it has passed over the flattening means and before it comes in contact with the drawing means.

6. In sheet glass apparatus, a receptacle containing a mass of molten glass, a bending roll, drawing means for drawing a sheet of glass from said mass, the said sheet being deflected over the bending roll to substantially a horizontal plane, means arranged between the bending member and the drawing means over which the sheet is dragged to flatten the same, means for heating the sheet as it is deflected over said means, and means arranged above the sheet for absorbing heat therefrom after it has passed over the flattening means and before it comes in contact with the drawing means.

7. In sheet glass apparatus, a receptacle 95 containing a mass of molten glass, drawing means for drawing a sheet of glass from said mass, means having a curved portion over which the sheet of glass is dragged, the curved portion producing a wiping effect for removing irregularities in the sheet surface, means for heating the sheet as it is passed over the curved portion of said member, and heat absorbing means arranged between said member and the drawing member for lowering the temperature of said sheet.

8. In sheet glass apparatus, a receptacle containing a mass of molten glass, drawing means for drawing a sheet of glass from said mass, means having a curved portion over which the sheet of glass is dragged, the curved portion producing a wiping effect for removing irregularities in the sheet surface, means for heating the sheet as it is passed over the curved portion of said member, and a cooler arranged between said member and the drawing member for lowering the temperature of said sheet.

9. In sheet glass apparatus, a receptacle containing a mass of molten glass, drawing means for drawing a sheet of glass from said mass, a slab arranged in advance of the drawing means and over which the sheet is dragged to flatten the same, means for controlling the temperature of said slab, means for heating the sheet as it is dragged over the slab, and a cooler arranged above the sheet to cool the same as it passes from the slab to the drawing means.

10. In sheet glass apparatus, a receptacle containing a mass of molten glass, drawing means for drawing a sheet of glass from said mass, a slab arranged in advance of the drawing means, and over which the sheet is dragged to flatten the same, means for absorbing heat from the slab, means for heating the sheet as it is dragged over the slab, and a cooler arranged above the sheet to cool the same as it passes from the slab to 10 the drawing means.

Signed at Toledo, in the county of Lucas and State of Ohio, this 27th day of January, 1925.

ARTHUR E. FOWLE.
